UNITED STATES PATENT OFFICE.

MONTAGUE STANLEY NAPIER, OF CANNES, FRANCE.

PISTON.

1,403,560.

Specification of Letters Patent. Patented Jan. 17, 1922.

Application filed October 27, 1920. Serial No. 419,959.

To all whom it may concern:

Be it known that I, MONTAGUE STANLEY NAPIER, a subject of the King of England, and residing at Cannes, Alpes Maritimes, in France, have invented certain new and useful Improvements in Pistons, of which the following is a specification.

This invention relates to pistons more particularly pistons intended for use in internal combustion engines which are formed wholly or as to their skirts of aluminium or aluminium alloy and has for its object to provide a construction which will obviate that movement of the piston against the walls of the cylinder which is commonly referred to as "slap" or "tap".

Where the piston is constructed of the same metal as is employed in the formation of the cylinder within which the piston is to move the occurrence of piston "slap" is avoided by allowing only a small clearance between the exterior of the piston and the inner wall of the cylinder. In the case of a piston constructed of aluminium or aluminium alloy or where the piston skirt is formed of this metal in the usual type of piston it is impossible to make the clearance between the piston and cylinder so small as to prevent "slap" from taking place owing to the difference in the coefficients of expansion of the aluminium or aluminium alloy and of the steel cylinder. "Slap" is considered to be due to the movement of the skirt of the piston against the walls of the cylinder while the head of the piston is prevented from such movement by the piston rings. It is apparent that the above mentioned defect may be overcome if the expansion of the skirt can be regulated to conform with the expansion of the cylinder. This end is attained by the present construction.

According to this invention the skirt of the piston is slit longitudinally or similarly formed and the minimum necessary clearance between the skirt and cylinder is maintained by means of two complete or unbroken rings each of which is formed of a metal which has a coefficient of expansion different from that of the metal of the skirt and substantially the same as the coefficient of the metal of which the cylinder is formed. The aluminium or aluminium alloy skirt is slit in several places longitudinally for a substantial part of its length and the two complete rings which are both formed of the

same metal having the desired co-efficient of expansion are disposed within the skirt and fixed thereto toward its outer end but so that the rings will not be in contact with the cylinder wall. Thus the skirt may be slit 60 longitudinally in two or more places and the two rings which may be formed of steel, iron or like metal are fixed within the skirt at or near its outer end the rings being preferably close to each other. Rivets are passed 65 through the rings into the divided parts of the skirt. The coefficient of expansion of the metal of which the rings are formed is such that the diameter of that part of the skirt which lies outside of or around the 70 rings will be determined by the expansion of the rings which will correspond with the expansion of the cylinder so that only the clearance necessary to permit of the desired sliding fit of the piston within the cylinder 75 will be maintained.

The invention may be carried out in various ways but the accompanying drawing which is a longitudinal sectional elevation of one construction of the improved piston 80 illustrates by way of example a formation that may be adopted in practice.

The piston comprises a head A and a skirt B formed integral therewith and having bosses C adapted to carry a gudgeon pin. 85 The piston is constructed wholly of aluminium or aluminium alloy and the skirt B is slit by making longitudinal cuts D therein these cuts being conveniently four in number and disposed at equal distances apart 90 around the skirt.

The employment of a single ring of metal having a coefficient of expansion different from that of the metal of which the piston skirt is formed comprises the subject matter 95 of the present applicant's companion application for United States Letters Patent Serial No. 419,715, filed October 26, 1920. In that case if the divided parts of the skirt are riveted or otherwise rigidly connected 100 to the ring in more than one place distortion of the skirt is liable to occur in some instances. This is avoided in the present invention by employing two continuous unbroken metal ring members E and F. Each 105 of these rings is preferably of less width than the single ring if it were used and the two rings are conveniently formed similar as if they constituted the two parts of a single ring which has been divided into equal por- 110

tions by a cut taken in a plane at right angles to the peripheral surface of the ring. It is desirable to provide each ring with an inwardly directed flange E' F' and the two 5 rings are disposed within the end of the skirt B close together but not quite in contact and with the one flange E' at or adjacent to the end of the skirt. The ring F is arranged with its flanged edge F' remote 10 from the adjacent edge of the ring E as shown in the drawing.

Both rings are connected to the divided parts of the skirt B by a series of rivets G and H the rivets G which pass through the 15 ring E being staggered in relation to the rivets H which pass through the ring F. The ring E is connected by only a single rivet G to each part of the skirt B and this rivet is located toward one edge of each 20 part. Similarly the ring F is connected by only a single rivet to each part of the skirt B but each of these rivets is disposed toward that edge of each part of the skirt which is opposite to that edge near which lies the 25 rivet G connecting that part of the skirt to the ring E. The result of this method of connecting the two rings to the several parts of the skirt B is that on expansion of the skirt the two rings will tend to rotate 30 in opposite directions. In some instances it may be preferable to sub-divide the skirt into a greater number of parts each of which is connected to a single ring in one place only so that one half of the parts of 35 the skirt will be thus connected to the one ring while the remaining portions of the skirt will be connected to the other ring.

With the above described construction the expansion of the skirt is controlled or 40 determined by the expansion of the rings E and F which are conveniently constructed of the same metal as is employed in the construction of the cylinder J within which the piston is to be employed, as for example, 45 cast iron or steel. Bronze or other suitable metal may, however, be employed in the formation of the rings. Since the rings will expand in substantially the same way and to the same extent as the cylinder J the 50 aluminium skirt B of the piston will have its external diameter maintained substantially constant in relation to the diameter of the cylinder. Thus the advantage of an aluminium bearing surface is maintained with- 55 out the disadvantage which results from the aluminium or aluminium alloy having a coefficient of expansion different from that of the metal of which the cylinder is formed.

The dimensions and form of each of the 60 rings E and F may vary as found desirable and if preferred each of these rings or one of them may be formed flat and without a flange such as E' or F'. The details of construction may be modified as desired and the 65 invention may be applied to pistons of

various types and either where the piston is formed wholly of aluminium or aluminium alloy or where the skirt is formed of this metal and is attached to a head formed of steel, iron or other metal.

70

What I claim as my invention and desire to secure by Letters Patent is:—

1. In a trunk piston the combination of a skirt having in it a plurality of slits extending longitudinally from its outer end 75 for a substantial part of its length toward the piston head, two continuous unbroken metal ring members both formed of a metal having a coefficient of expansion which is different from that of the metal of which 80 the skirt is formed, and means whereby the ring members are attached to the divided parts of the skirt adjacent to the outer end of the latter, the ring members being so formed and positioned in the skirt that they 85 will not be in contact with the wall of the cylinder in which the piston is used but will be operative to maintain substantially constant the minimum necessary clearance between the skirt and the cylinder wall as 90 set forth.

2. In a trunk piston the combination of a head, a skirt formed integral with the head having in it a plurality of slits extending longitudinally from its outer end for a sub- 95 stantial part of its length toward the piston head, two continuous unbroken metal ring members both formed of a metal having a coefficient of expansion which is different from that of the metal of which the 100 skirt is formed but which is substantially the same as that of the metal of the cylinder in which the piston is to be used, and means whereby the ring members are attached to the divided parts of the skirt adjacent to 105 the outer end of the latter, the ring members being so formed and positioned in the skirt that they will not be in contact with the wall of the cylinder in which the piston is used but will be operative to maintain sub- 110 stantially constant the minimum necessary clearance between the skirt and the cylinder wall as set forth.

3. In a trunk piston the combination of a skirt having in it a plurality of slits extending longitudinally from its outer end for a substantial part of its length towards the piston head, two continuous unbroken metal ring members which are formed similar each having a thickening at one edge on its inner 115 side and both members being formed of a metal having a coefficient of expansion which is different from that of the metal of which the skirt is formed, and means whereby the ring members are attached to the divided parts of the skirt adjacent to the outer end of the latter, the ring members being so formed and positioned in the skirt that they 120 will not be in contact with the wall of the cylinder in which the piston is used but will 125 be operative to maintain substantially constant the minimum necessary clearance between the skirt and the cylinder wall as set forth.

125

130

be operative to maintain substantially constant the minimum necessary clearance between the skirt and the cylinder wall as set forth.

5 4. In a trunk piston the combination of a skirt having in it a plurality of slits extending longitudinally from its outer end for a substantial part of its length towards the piston head, a continuous unbroken metal 10 ring member which is placed within the skirt towards its outer end and lies in contact with the inner wall of the divided parts of the skirt, a second and similar continuous unbroken metal ring member which is placed 15 within the skirt adjacent to but on the inner side of the first ring member and not in contact therewith, both ring members being formed of a metal having a coefficient of expansion which is different from that of 20 the metal of which the skirt is formed, and means whereby the ring members are separately attached to the divided parts of the skirt, the ring members being operative to maintain substantially constant the minimum 25 necessary clearance between the skirt and the cylinder wall as set forth.

5. In a trunk piston the combination of a skirt having in it a plurality of slits extending longitudinally from its outer end for a substantial part of its length towards the piston head, two continuous unbroken metal ring members formed of a metal having a coefficient of expansion which is different from that of the metal of which the skirt is 30 formed, and rivets extending through the ring members and the divided parts of the skirt so as to rigidly connect each ring member to the skirt, the ring members being so formed and positioned in the skirt that they 35 will not be in contact with the wall of the cylinder in which the piston is used but will be operative to maintain substantially constant the minimum necessary clearance between the skirt and the cylinder wall as set forth.

6. In a trunk piston the combination of a skirt having in it a plurality of slits extending longitudinally from its outer end for a substantial part of its length towards the piston head, two continuous unbroken metal ring members each having a smooth periphery adapted to lie within the skirt against its inner wall and each having at one edge a thickening constituting an inwardly directed flange, both ring members being 50 formed similar and of a metal having a coefficient of expansion which is different from that of the metal of which the skirt is formed, and means whereby the ring members are 55 attached to the divided parts of the skirt adjacent to the outer end of the latter, the ring members being so formed and positioned in the skirt that they will not be in contact with the wall of the cylinder in 60 which the piston is used but will be operative 65

to maintain substantially constant the minimum necessary clearance between the skirt and the cylinder wall as set forth.

7. In a trunk piston the combination of a skirt having in it a plurality of slits extending longitudinally from its outer end for a substantial part of its length toward the piston head, two continuous unbroken metal ring members formed of a metal having a coefficient of expansion which is different from that of the metal of which the skirt is formed, rivets extending through one of the ring members and each of the divided parts of the skirt at a point situated adjacent to one longitudinal edge of each divided part, 70 and rivets extending through the second ring member and each of the divided parts of the skirt at a point situated adjacent to that longitudinal edge of each part of the skirt which is opposite to that edge near to which the first ring is attached, the rivets serving to rigidly connect both ring members to the skirt and the ring members being so formed and positioned in the skirt that they will not be in contact with the wall of 75 the cylinder in which the piston is used but will be operative to maintain substantially constant the minimum necessary clearance between the skirt and the cylinder wall as set forth.

8. In a trunk piston the combination of a skirt having in it a plurality of slits extending longitudinally from its outer end for a substantial part of its length toward the piston head, a continuous unbroken metal ring member which is placed within the skirt toward its outer end and lies in contact with the inner wall of the divided parts of the skirt, a second and similar continuous unbroken metal ring member which is placed 80 within the skirt adjacent to but on the inner side of the first ring member and not in contact therewith, both ring members being formed of a metal having a coefficient of expansion which is different from that of the metal of which the skirt is 85 formed, rivets extending through the first ring member and each of the divided parts of the skirt at a point situated adjacent to one longitudinal edge of each divided part, and rivets extending through the second ring member and each of the divided parts of the skirt at a point situated adjacent to that longitudinal edge of each part of the skirt which is opposite to that edge near to which the first ring is attached, the rivets serving to rigidly connect both ring members to the skirt and the ring members being so formed and positioned in the skirt that they will not be in contact with the wall of 90 the cylinder in which the piston is used but will be operative to maintain substantially constant the minimum necessary clearance between the skirt and the cylinder wall as set forth.

9. In a trunk piston the combination of a 95

skirt having in it a plurality of slits extending longitudinally from its outer end for a substantial part of its length toward the piston head, two continuous unbroken metal ring members formed of a metal having a coefficient of expansion which is different from that of the metal of which the skirt is formed, and rivets extending through the ring members and the divided parts of the skirt so as to rigidly connect each ring member to each part of the skirt the rivets which pass through the one ring member being disposed so as to alternate with the rivets which pass through the second ring member, the ring members being so formed and positioned in the skirt that they will not be in contact with the wall of the cylinder in which the piston is used but will be operative to maintain substantially constant the minimum necessary clearance between the skirt and the cylinder wall as set forth.

10. In a trunk piston the combination of a skirt having in it a plurality of slits extending longitudinally from its outer end for a substantial part of its length toward the piston head, a continuous unbroken metal ring member which has at one edge a thickening constituting an inwardly directed flange the periphery of the member lying in contact with the inner wall of the divided parts of the skirt and being placed within the skirt toward its outer end with the flanged edge adjacent to the end of the skirt, a second and similar continuous unbroken metal ring member which is placed within the skirt adjacent to but on the inner side of the first ring member and not in contact therewith with its flanged edge remote from the adjacent edge of the first ring member, both ring members being formed of a metal having a coefficient of expansion which is different from that of the metal of which the skirt is formed, and means whereby the ring members are separately attached to the divided parts of the skirt the ring members being operative to maintain substantially constant the minimum necessary clearance between the skirt and the cylinder wall as set forth.

11. In a trunk piston the combination of a skirt having in it a plurality of slits extending longitudinally from its outer end for a substantial part of its length toward the piston head, a continuous unbroken metal ring member which has at one edge a thickening constituting an inwardly directed flange the periphery of the member lying in contact with the inner wall of the divided parts of the skirt and being placed within the skirt toward its outer end with the

flanged edge adjacent to the end of the skirt, a second and similar continuous unbroken metal ring member which is placed within the skirt adjacent to but on the inner side of the first ring member and not in contact therewith with its flanged edge remote from the adjacent edge of the first ring member, both ring members being formed of a metal having a coefficient of expansion which is different from that of the metal of which the skirt is formed, and rivets extending through the ring members and the divided parts of the skirt so as to rigidly connect each ring member to each part of the skirt the rivets which pass through the one ring member being disposed so as to alternate with the rivets which pass through the second ring member, the ring members being operative to maintain substantially constant the minimum necessary clearance between the skirt and the cylinder wall as set forth.

12. In a trunk piston the combination of a skirt having in it a plurality of slits extending longitudinally from its outer end for a substantial part of its length toward the piston head, a continuous unbroken metal ring member which has at one edge a thickening constituting an inwardly directed flange the periphery of the member lying in contact with the inner wall of the divided parts of the skirt and being placed within the skirt toward its outer end with the flanged edge adjacent to the end of the skirt, a second and similar continuous unbroken metal ring member which is placed within the skirt adjacent to but on the inner side of the first ring member and not in contact therewith with its flanged edge remote from the adjacent end of the first ring member, both ring members being formed of a metal having a coefficient of expansion which is different from that of the metal of which the skirt is formed, rivets extending through one of the ring members and each of the divided parts of the skirt at a point situated adjacent to one longitudinal edge of each divided part, and rivets extending through the second ring member and each of the divided parts of the skirt at a point situated adjacent to that longitudinal edge of each part of the skirt which is opposite to that edge near to which the first ring is attached, the rivets serving to rigidly connect both ring members to the skirt and the ring members being operative to maintain substantially constant the minimum necessary clearance between the skirt and the cylinder wall as set forth.

In testimony whereof I have signed my name to this specification.

MONTAGUE STANLEY NAPIER.
